CLAIM

The ornamental design for dispenser for small item, as shown and described.

DESCRIPTION

FIG. 1 is a top, front, right perspective view of a dispenser for small item made in accordance with our new design;

FIG. 2 is a front view of the embodiment of FIG. 1;

FIG. 3 is a back view of the embodiment of FIG. 1;

FIG. 4 is a top plan view of the embodiment of FIG. 1;

FIG. 5 is a bottom plan view of the embodiment of FIG. 1; and,

FIG. 6 is a left side elevational view of the embodiment of FIG. 1, with the right side elevational view being the mirror image of the left side elevational view.
